UNITED STATES PATENT OFFICE.

VICTOR RASHKIS, OF ROCKAWAY PARK, AND MAX RASHKIS, OF BROOKLYN, NEW YORK.

PUTTEE.

1,260,449.

Specification of Letters Patent. Patented Mar. 26, 1918.

Application filed September 26, 1917. Serial No. 193,294.

To all whom it may concern:

Be it known that we, VICTOR RASHKIS and MAX RASHKIS, citizens of the Republic of Russia residing at Rockaway Park, Queens county, Long Island, and Brooklyn, Kings county, State of New York, respectively, have invented certain new and useful Improvements in Puttees, of which the following is a specification.

10 Our invention relates particularly to both the form and construction of cloth or woven puttees and also to the process of manufacture by which the puttees are produced.

15 In the present method of manufacture of cloth puttees, straight strips of the required width are cut parallel with the length of the goods from which the puttees are to be made, so that the weave runs lengthwise and at right angles in the finished article 20 and renders the same inelastic, resistant and unadaptable to smoothly and neatly spiraling the leg of the wearer. This is highly objectionable owing to the time and effort required in attempting to avoid and conceal 25 the fullness which develops along one edge, as the strip is wound about the leg.

Further, in the present cloth puttee, it is customary to attach a long piece of tape, which is spirally wound over the puttee 30 proper to secure it in position and against loosening and unwinding and the free end of the tape is usually tucked in under a fold of the puttee. This also is objectionable owing to the time and care required in applying the tape and the insecure fastening for 35 the free end thereof.

Recognizing these disadvantages, we have produced a puttee, of a form and construction, which, it is believed, successfully overcomes and completely remedies the objectionable features above referred to.

In the production of our improved puttee, the first step in the process of manufacture is to cut straight strips of the required width 45 on the bias or diagonally of the goods from which the puttees are to be made. This brings the weave of the cloth at decided angles to the length of the strip and renders the latter elastic, yielding and adaptable to 50 shaping.

The next step consists in giving the straight strip the necessary curvature and permanent set, to cause it, when applied to the leg, to at once readily adapt itself to the 55 spiral form of winding and properly fit and closely hug the leg form, without showing

surplus material or fullness at any point. This is accomplished by shrinking and pressing the strip along one edge, while at the same time stretching it along the opposite 60 edge and results in giving the strip a permanent curvature, approximately equal to a 120 degree arc.

The operation of shrinking and stretching, above referred to, is successfully accomplished only by workmen familiar with handling cloth and who possess considerable skill in this class of work. This is due to the fact that the length of the one edge must be increased by stretching in definite relation to 70 the length of the other edge, which is reduced by shrinking, in order to produce the curvature necessary for adapting the finished puttee to properly spiral the leg of the wearer. The workmen are therefore 75 called upon to exercise their own judgment as to the proper treatment for the opposite edges of the puttee blank. In giving such a blank curvature, the practice is to progressively moisten the cloth along one edge, and, 80 while applying the pressing iron to the dampened edge of the blank and holding it firmly under pressure of the iron, to stretch the opposite edge with the free hand. This treatment applied throughout the 85 length of the blank produces the desired curvature.

The third step, while not absolutely essential to the production of our improved puttee, is both important and desirable for 90 many reasons and consists in waterproofing the article by the well known process. This contributes to the permanency of the curvature and renders it much more agreeable to handle in use; at the same time adding 95 vastly to the comfort of the wearer.

The final step consists in attaching a short strap and buckle to one end of the curved cloth strip for securing it at the final turn of the spiral winding.

In the accompanying drawings, forming part of this specification, we have illustrated a puttee constructed in accordance with our invention. We wish it understood, however, that we do not limit ourselves to either the 105 exact details or the specific form shown, as various changes may be made therein without the meaning of the present invention.

In the drawings:

Figure 1 is a view showing the bias cutting of the straight strips from the cloth of which the puttees are to be made.

Fig. 2 shows one of the strips thus cut.

Fig. 3 shows the strip, after being shrunk and pressed along one edge and stretched along the other, given the curvature necessary to adapt it to properly spiraling the leg.

Fig. 4, shows the curved strip with the fastening strap attached, and

Fig. 5 shows the improved puttee in use.

Referring now to the drawings;

The cloth or other woven fabric from which the puttees are to be made, is illustrated at 1, and diagonally thereof are shown the lines 2, of bias cutting to produce straight strips 3, of the required width, in which the weave of the cloth, indicated by the lines 4 and 5, runs at more or less of an angle to the length thereof.

As described above, this straight strip 3, is given permanent curvature, as shown in Fig. 3, approximating an arc of about 120 degrees, to adapt it to the spiral winding about the leg and the material is then waterproofed in the usual manner, which it is not deemed necessary to describe, as it is well known in the art.

The strip having now been reduced to the proper curved form, the fastening strap 6,

and buckle 7, are attached at one end thereof, as shown in Fig. 4, and the puttee is complete and ready for use.

Having, therefore, described our invention, we claim:

1. The method of manufacture of spiral puttees, which comprises dividing the material from which the puttees are to be made to produce strips of the required width and length, and then giving such strips permanent curvature to adapt them to spiral winding by shrinking and pressing the strips along one edge while simultaneously stretching the opposite edge.

2. The method of manufacture of spiral puttees from woven fabric, which comprises dividing the material from which the puttees are to be made, by bias cuts, to produce strips of the required width and length, and then giving the strips permanent curvature to adapt them to spiral winding by shrinking and pressing the strips along one edge while simultaneously stretching the opposite edge.

VICTOR RASHKIS.
MAX RASHKIS.
